UNITED STATES PATENT OFFICE.

HANNS KLEMM, OF SINDELFINGEN, GERMANY, ASSIGNOR TO DAIMLER-MOTOREN-GESELLSCHAFT, OF STUTTGART-UNTERTURKHEIM, GERMANY, A CORPORATION OF GERMANY.

HINGE FOR WINDOWS AND DOORS OF MOTOR CARS.

Application filed March 17, 1924. Serial No. 699,732.

To all whom it may concern:

Be it known that I, HANNS KLEMM, a citizen of the State of Wurttemberg, Germany, residing at Sindelfingen, Wurttemberg, Germany, Bahnhofstrasse 38, have invented certain new and useful Improvements in a Hinge for Windows and Doors of Motor Cars, of which the following is a specification.

- 10 This invention is the result of the endeavour to provide for motor-cars, more especially for motor cars with removable and collapsible hood, in which the axis of the hinges of the window positioned above the door is out of line with the axis of the hinges of the door, such devices as will permit the window and door to retain the relative position, which they have to each other in the closed state, also when they are open.
- 15 20 In order to accomplish this object there is provided according to the present invention, a hinge for the window, by applying which the window is attached to the top of the car body by means of a connecting arrangement flexible in itself, and also shiftable, so that door and window will keep their relative position to each other in the closed state also when they are thrown open, as an example of this invention the hinge may be formed in such a manner, that the shank of one side of the hinge is provided with a joint and that the shank and the shank-support are movable against each other.

In the drawing an example of the invention has been represented diagrammatically in two views, in which Fig. 1 is a view of a part of a motor-car with the door closed and the window also closed.

Fig. 2 is a plan view and sectional view with the door opened and with the window opened and Fig. 3 is a fragmentary section of a motor-car with the door in its open position.

The motor-car (a), for example, is provided with a removable body-top (b), which is collapsible. Attached to the body-top (b), by means of hinges, is the window (c), which is in mechanical relation to the door (d). It must be possible to open and to close the door (d) and the window (c) together in the well known manner. However, as is evident in the drawing, the axis (e) of the hinges (e') and (e²) of the window (c) is out of line with the axis (f) of

the hinges (f') of the door (d). In order to connect the window (c) and the door (d) with each other in such a manner, that they will not alter their relative positions in the closed state or on being opened, there is, for example, a further hinge (g) provided in the frame-member or shank (e³) of the hinges (e') and (e²); attached to hinge (g), and forming a continuation thereof, is a guiding element or rod (h), which, according to the example, engages a sleeve (i) attached to the frame of the window (c) so as to be slidable therein.

As is shown in Fig. 2, the window (c) has the same relative position to the door (d) in the open state as well as in the closed state.

After having thus described the invention, what I claim is:

1. A hinge for windows and doors of motor cars, more especially for motor cars with detachable and collapsible tops and with the axis of the door-hinges displaced against the axis of the window hinges, in combination with a hinge member connecting the window with the top of the car body, said hinge member being flexible and adapted to be shifted, substantially as described.

2. A hinge for windows and doors of motor cars, more especially for motor cars with detachable and collapsible tops and with the axis of the door hinges, displaced against the axis of the window hinges, in combination with a hinge member connecting the window with the top of the car body, said hinge member being flexible and adapted to be shifted and to cause the door and the window to retain their relative position to each other as well in closed as also in opened state, substantially as described.

3. A hinge for windows and doors of motor cars, more especially for motor cars with detachable and collapsible tops and with the axis of the door hinges displaced against the axis of the window hinges, in combination with a hinge member connecting the window with the top of the car body, said hinge member being flexible and adapted to be shifted and to cause the door and the window to retain their relative position as well in closed as also in opened state said hinge member forming one shank-fitting of the general hinge and said shank-fitting being jointed and arranged so that the fitting

is adapted to be shifted in relation to the fitting-support, substantially as described.

4. A hinge for windows and doors of motor cars, more especially for motor cars with detachable and collapsible tops and with the axis of the door hinges displayed against the axis of the window hinges, in combination with a hinge member connecting the window with the top of the car body, said hinge member being flexible and adapted to be shifted and to cause the door and the window to retain their relative position to each other as well in closed as also in opened state, said hinge member forming one shank-fitting of the general hinge, said shank-fitting being jointed and arranged so that the fitting is adapted to be shifted in relation to the fitting-support, said shank-fitting jointed in the fitting-portion engaging the window frame, substantially as described.

5. A hinge for windows and doors of motor cars, more especially for motor cars with detachable and collapsible tops and with the axis of the door hinge displaces against the axis of the window hinges, in combination with a hinge member connecting the window with the top of the car body, said hinge

member being flexible and shiftable and forming one shank-fitting of the general hinge, said shank-fitting being jointed in the fitting-portion engaging the window frame and one portion of the jointed fitting engaging a suitable portion of the window frame so as to be shiftable, substantially as described.

6. In an automotive vehicle of the open car type, the combination of a body, a door hinged thereon, a window comprising an independent element and located in mechanical relation to said door, a hinged frame-member mounted upon said body, the axis of the hinges of said frame-member and the hinges of said door being out of line with each other, sleeves located at opposite horizontal edges of said window, rods slidable in said sleeves and pivotal connections between said rods and frame-member.

In testimony whereof I affix my signature in presence of two witnesses.

HANNS KLEMM.
